UNITED STATES PATENT OFFICE.

RIDGELEY B. PIERSON, OF QUINCY, ILLINOIS.

COMBINATION CUFF.

Application filed January 23, 1924. Serial No. 687,977.

To all whom it may concern:

Be it known that I, RIDGELEY B. PIERSON, a citizen of the United States of America, residing at Quincy, in the county of Adams and State of Illinois, have invented certain new and useful Improvements in Combination Cuffs, of which the following is a specification.

This invention relates to certain new and useful improvements in combination cuffs permanently attached to the wrist end of a shirt sleeve and being constructed in a manner for use either as a straight or French cuff.

15 The primary object of the invention is to provide a combination cuff for shirt sleeves wherein a shirt cuff capable of being worn as the straight cuff type is provided with a flap or cuff extension secured to the inner side thereof and foldable upon a line when the straight type of cuff is used slightly spaced inwardly of the outer edge of the straight cuff to hide from view or eliminate any crease that might be formed 25 when the flap or cuff extension is moved outwardly and folded over the straight cuff to produce a cuff of the French type.

Another object of the invention is to provide a shirt cuff of the above type wherein 30 a single button secured to the inner face of the inner cuff side is adapted to be passed through buttonholes formed in the flap or cuff extension and the outer straight side of the cuff when the flap or cuff extension 35 is folded inwardly to present the straight type of cuff with the retaining button viewable only at the outer side of the cuff.

With the above general objects in view and others that will become apparent as the 40 nature of the invention is better understood, the same consists of the novel form, combination and arrangement of parts herein-after more fully described, shown in the accompanying drawing and claimed.

45 In the drawing, wherein like reference characters designate corresponding parts throughout the several views,

50 Figure 1 is a perspective view of a combination shirt cuff constructed in accordance with the present invention, the flap or cuff extension being illustrated in an extended

position capable of being folded either inwardly or outwardly of the main cuff section.

Figure 2 is a perspective view showing 55 the cuff extension folded inwardly presenting a straight cuff effect,

Figure 3 is a perspective view showing 60 the cuff extension folded outwardly to present a French cuff, and

Figure 4 is a longitudinal sectional view 65 of the cuff extension and cuff in the position shown in Fig. 1.

In the accompanying drawings, the reference numeral 1 designates the wrist end of 65 a shirt sleeve to which a straight cuff 2 is permanently attached as by stitching along the line 3.

The straight cuff 2 is preferably of double 70 ply construction and a double ply flap 4 is secured to the inner face of the straight cuff, the inner edge thereof being secured by the stitching 3 to the wrist end of the shirt sleeve 1 and straight cuff 2 while the flap 4 is further secured adjacent the outer 75 end of the straight cuff 2 at the point 5 resulting in a flange extension 6 carried by the straight cuff 2.

The cuff flap 4 carries an extension 7 of 80 general cuff formation and provided with registering button holes 8 while the straight cuff 2 and inner flap 4 are provided with registering button holes 9 that preferably extend at right angles to each other, while a button 10 is secured to the inner face of 85 the inside section of the cuff, the button 10 being located for passage through the openings 8 in the flap extension 7 and the opposite opening 9 when the flap extension 7 is folded inwardly to present the straight 90 cuff effect.

The flap or cuff extension 7 is illustrated in an extended position in Fig. 1 and may be moved either inwardly of the straight cuff 2 or outwardly thereof to overlie the 95 same. Figure 2 shows the cuff extension 7 folded inwardly with the button 10 passed through the registering button holes 8 and 9 with the flange edge 6 of the straight cuff 2 projecting beyond the folded edge of 100 the cuff extension 7. In this position, the extension 7 is entirely hidden from view

and the cuff presents the straight type effect present in certain styles of shirts. When the cuff extension 7 is folded outwardly to overlie the straight cuff 2 as shown in Fig. 3, the several button holes 8 and 9 register and an ordinary cuff link may be passed therethrough. When the cuff extension 7 is so folded, any crease that might have resulted by folding the extension inwardly as shown in Fig. 2, will not be exposed to view and the detrimental effect of a folding reversible cuff is eliminated, the combination cuff being folded to present either a straight or French cuff with any crease or fold entirely hidden from view. The edge flange 6 at the outer edge of the straight cuff 2 is disposed outwardly of the fold of the cuff extension with the extension positioned inwardly of the outer edge of the straight cuff when folded for the straight cuff effect. The button 10 is employed when the extension is folded inwardly with the effect of a single straight cuff secured in a closed position by a button attached to the shirt cuff.

While there is herein shown and described the preferred embodiment of the present invention, it is nevertheless to be understood that minor changes may be made therein

without departing from the spirit and scope 30 of the invention as claimed.

What is claimed as new is:—

1. In a combination shirt cuff, a straight cuff section, and a cuff extension foldable upon a line inwardly of and close to the outer edge of the straight cuff for giving either a straight or French cuff effect and the connection between the straight cuff and extension being spaced inwardly of and close to the outer edge of the straight cuff 40 and at the inner side of the straight cuff.

2. In a combination shirt cuff, a straight cuff section, a cuff extension foldable upon a line inwardly of and close to the outer edge of the straight cuff for giving either 45 a straight or French cuff effect and the connection between the straight cuff and extension being spaced inwardly of and close to the outer edge of the straight cuff, a button secured to the inner side of the 50 straight cuff and said straight cuff and extension having cuff link openings adapted to register when the extension is folded outwardly to produce the French effect.

In testimony whereof I affix my signature.

RIDGELY B. PIERSON.
